CLAIM

The ornamental design for beverageware, as shown and described.

DESCRIPTION

FIG. 1 is a perspective view of an embodiment of beverageware showing my new design;

FIG. 2 is a left side elevational view thereof;

FIG. 3 is a right side elevational view thereof;

FIG. 4 is a rear elevational view thereof;

FIG. 5 is a front elevational view thereof;

FIG. 6 is top plan view thereof;

FIG. 7 is bottom plan view thereof; and,

FIG. 8 is a exploded perspective view thereof.

The oblique shade lines of FIGS. 1-6 and 8 indicate a transparent or translucent surface.

1 Claim, 7 Drawing Sheets
